ABSTRACT: An easy opener container comprising a metal can having one end wall with a scored tab within the central area thereof, the tab having an upwardly domed push button secured thereto, the button being used to urge the tab downwardly so to rip the score line, and the underside of the tab having a leaf spring pulling the tab the leaf spring takes its normal curved shape and thus open in the can.

INVENTOR
PEDRO CHAGOYEN

PUSH-BUTTON SELF-OPENER CAN

This invention is a self-opening metal can, such as used for beverages such as beer or soft drinks.

A principle object of the present invention is to provide a push button self-opener can which incorporates a novel structure for opening the same with certain advantages.

Another object of the present invention is to provide a push button self-opener can wherein the upper end of the can includes a scored tab that is downwardly depressed so to rip open the edges thereof for gaining access to the beverage or the like.

Yet another object is to provide a push button self-opening can wherein the tab remains integral with the can and accordingly eliminates the usual littering of pull tabs torn off beverage cans.

Other objects of the present invention are to provide a push button self-opener can which is simple in design, rugged in construction, inexpensive to manufacture, easy to use and efficient in operation.

These and other objects will be readily evident upon a study of the following specification and the accompanying drawing wherein:

FIG. 1 is top plan view of a can incorporating the present invention, and

FIG. 2 is side elevation view thereof shown partly in cross section.

Referring now to the drawing in detail, the reference numeral 10 represents a push button self-opener can, according to the present invention, wherein there is a metal can 11 comprised of a cylindrical sidewall 12 that is sealed at its upper and lower ends to an upper circular end wall 13 and a circular lower end wall 14. The cylindrical sidewall and the end walls enclose compartment 15 within which a beverage or other substance may be contained.

The upper end wall 13 has a tab 16 scored in a central area thereof, the tab being defined generally by a substantially U-shaped score line 17. At one end of the tab 16, there is secured a molded dome or button 18 upon the upper side of the tab so to serve as a means against which a person may push when attempting to open the can. It will be noted, as shown in FIG. 1 of the drawing, that in the vicinity of the dome, the generally U-shaped score line 17 protrudes in outline so as to present a

score line extending semicircularly relatively close to the edge of the dome, thus making it easier for a person to tear the score line with less pressure.

A leaf spring 19 is positioned adjacent the underside of the tab, the spring 19 being secured at one end to a rivet 20 attached to the can end 13. The opposite end of the spring is attached to the dome 18.

In operative use, by pressing the dome on the top of the can, the ripping of the score line is started, and at the same time, 10 the pressure on the dome helps one end of the spring to start the opening of the can, since the spring will tend to go in its normal curved shape carrying with it the preconfigured tab, thus opening the can. In this form of the invention, it is of course understood that the spring at normal rest is of arcuate 15 configuration, thereby retaining the tab in an open position after the can is opened.

The present device may also be used for containers for sugar, salt, cereals or the like.

I claim:

- 20 1. In an easy opening can having a sidewall and an upper and a lower end wall which enclose a central compartment, improved means for opening the can comprising a tab having an upwardly extending dome at one end and an edge defined by a generally U-shaped score line in the upper end wall; and a
- 25 leaf spring having one end secured to the upper end wall of the can adjacent one end of said tab, and its opposite end secured to the opposite end of said tab, whereby the can may be opened by an application of pressure on said dome.
2. The combination set forth in claim 1 wherein said score line extends relatively close to an edge of said dome to facilitate opening the can along said score line.
- 30 3. The combination set forth in claim 1 wherein said leaf spring has an arcuate shape in its relaxed position and retains said tab in an arcuate position after the can is opened.
- 35 4. The combination set forth in claim 1 wherein said leaf spring is adjacent the underside of said tab.
5. The combination set forth in claim 1 wherein said dome is a member which is secured to and extends through said tab.
6. The combination set forth in claim 5 wherein said opposite end of said leaf spring is secured to said dome.
- 40 7. The combination set forth in claim 1 wherein said one end of said leaf spring is riveted to the upper end wall.

UNITED STATES PATENT OFFICE
CERTIFICATE OF CORRECTION

Patent No. 3,557,999

Dated January 26, 1971

Inventor(s) Pedro Chagoyen

It is certified that error appears in the above-identified patent and that said Letters Patent are hereby corrected as shown below:

The address of the inventor should be

--81-07 25th Avenue

Jackson Heights, Queens, N.Y. 11370--

Signed and sealed this 11th day of May 1971.
